UNITED STATES PATENT OFFICE.

THOMAS JOSEPH SCHUETZ, OF TULSA, OKLAHOMA, ASSIGNOR TO BRADEN STEEL & WINCH COMPANY, OF TULSA, OKLAHOMA.

TAKE-UP REEL.

Application filed December 27, 1926. Serial No. 157,374.

My invention consists in new and useful improvements in wire or cable take-up reels, and has for its object to provide a device of this character, adapted to be used in connection with motor vehicles equipped with winches of the type shown and described in my co-pending applications Serial Nos. 62,065 and 62,066.

A further object of my invention is to provide a take-up reel adapted for reeling telephone and telegraph wires, fence wires etc., of the usual diameters and compositions, into neat and compact coils, and having means for facilitating the removal of said coiled reels from said device.

A still further object of my invention is to provide a take-up reel which is easily operated, thus saving considerable time in the performance of its function, and one which will produce a regularly wound coil which, when removed from the device, presents a perfect circle on its inside circumference, rather than being bent or formed in polygonal shapes, which tend to break galvanizing, causing kinks and greatly reducing the strength of the wire or cable.

With the above and other objects in view which will appear as the description proceeds, my invention consists in the novel features herein set forth, illustrated in the accompanying drawings and more particularly pointed out in the appended claims.

Referring to the drawings, in which numerals of like character designate similar parts throughout the several views,

Fig. 1 is a perspective view of my improved wire take-up reel applied to a winch on the rear wheel of a motor vehicle.

Fig. 2 is a cross sectional view of an assembled take-up reel, showing the winch in dotted lines.

Figs. 3 and 4 are perspective views of the outer and inner members respectively, which together form the take-up reel,

Fig. 5 is a view of a portion of the take-up reel taken on line 5-5 of Fig. 2.

In the drawing, 1 designates a cylinder of suitable dimensions to fit over the cable drum α of a winch of the type shown and described in the pending applications aforementioned. Welded or otherwise permanently secured to the cylinder 1 is a circumferential flange 2, at a point near its inner extremity 3. At the base of this flange 2, and either integral therewith or permanently secured

thereto, and to the cylinder 1, I provide a circumferential inclined plane or beveled ring 4, inclined downwardly toward the outer end of said cylinder, as clearly shown in Figs. 2 and 4. 5 represents a plurality of internally threaded lugs, permanently secured at predetermined points around the inner surface of the cylinder 1, at its outer extremity, the function of which will be hereinafter set forth. This cylinder and flange, 60 as just described, comprise the inner member A of the take-up reel.

The outer member B of the device consists of a circular ring-like disc 6 of substantially the same outside diameter as the flange 2, 70 and of an inside diameter suitable to accommodate the cover of the winch to which the device is to be applied. To the inner side of this disc 6, I secure by riveting or other suitable means, a plurality of angle spring bars 7, the free arms of which extend at approximately right angles to the disc 6, and being of a length slightly greater than the distance between the flange 2 and the outer extremity of the cylinder 1, for the purpose herein-after described. The free ends of the bars 7 form a circle which when in normal position, or when not engaging the inner member A of the reel, is of a slightly lesser diameter than the circle formed by the ends immediately adjacent the disc 6.

The assembling and operation of the device is as follows:

The spring bars 7 of the member B are slipped over the outer surface of the cylinder 1 of the member A until the free ends of said bars abut the flange 2, having been expanded by the beveled ring 4, as shown in Fig. 2. Wing bolts 8 are then inserted in the apertures 9 in the disc 6 and screwed through the threaded lugs 5 on the cylinder 1, and into threaded apertures provided in the outer flange α' of the winch α . This operatively secures the take-up reel in place on the winch and retains the members A and B of said reel in fixed relation to one another, the inner faces of the lugs 5 being brought into immediate contact with the outer flange α' of the winch α , but leaving a clearance at 10, (Fig. 2) to insure complete contact of the free ends of the bars 7 against the flange 2, due to the slightly greater length of the spring bars, as before mentioned.

After the device has been assembled, the

winch is set in operation and the wire or cable reeled on the outer surfaces of the spring bars 7, into a neat, compact coil.

To remove the coil from the reel, the bolts 8 are removed and the member B with the coil thereon, slipped off of the cylinder 1 of the member A. The spring bars 7 immediately retract and return to their normal position, relieving all pressure against the inner surface of the coil, due to their spring material, and the coil of wire is easily removed therefrom.

From the foregoing, it is believed that my invention may be clearly understood without further description, it being borne in mind that numerous changes may be made in the details of construction without departing from the spirit of the invention, as set out in the appended claims.

20 What I claim and desire to secure by Letters Patent is:

1. A take-up reel comprising an inner member adapted to be mounted in connection with the driving wheel of a motor vehicle, 25 an outer member adapted to be slipped over said inner member, means for securing said members together, and means for causing a portion of said outer member to expand when in engaging position, and contract when in non-engaging position, whereby the removal of a reel of wire or the like is facilitated.

2. In combination with a winch applied to the driving wheel of a motor vehicle, a 35 take-up reel comprising an inner member adapted to be mounted over said winch, an outer member adapted to be slipped over said inner member, means for securing said members together and in operative engagement with said winch, and means for causing a portion of said outer member to expand when in engaging position, and contract when in non-engaging position, whereby the removal of a reel of wire or the like is 45 facilitated.

3. A take-up reel comprising an inner member adapted to be mounted over a winch secured to the driving wheel of a motor vehicle, an outer member having a resilient 50 portion adapted to be slipped over said inner member, means on said inner member for

causing the expansion of said resilient portion when in engaging position, and means for securing said members together and in operative engagement with said winch. 55

4. In combination with a winch secured to the driving wheel of a motor vehicle, a take-up reel consisting of an inner member which comprises a cylinder adapted to fit over said winch, having a circumferential flange extending therefrom, an outer member comprising a disc portion having a plurality of spring members secured thereto, said spring members being adapted to be slipped over said cylinder of said inner member, means 60 on said inner member for causing the expansion of said springs, and means for securing said inner and outer members together for operatively engaging the winch. 65

5. A take-up reel as claimed in claim 4, 70 wherein said means for expanding the spring members consists of a beveled ring on said cylinder immediately adjacent said flange.

6. In combination with a winch secured to the driving wheel of a motor vehicle, a take-up reel comprising an inner member consisting of a cylinder adapted to fit over said winch and having a circumferential flange extending therefrom, a beveled ring on said cylinder immediately adjacent said flange, a plurality of internally threaded lugs on the inner surface of said cylinder at its outer extremity, an outer member comprising a disc having a plurality of angle spring bars 75 secured thereto, the free arms of said bars extending approximately at right angles thereto, said spring bars being adapted to be slipped over said cylinder, and expanded by said beveled ring on said inner member, a 80 plurality of apertures in said disc member arranged adjacent said internally threaded lugs on said inner member, and bolts adapted to be inserted through said apertures and screwed through said lugs into apertures 85 provided in the outer wall of said winch, whereby said inner and outer members are 90 secured together and operatively engage said winch. 95

In testimony whereof I affix my signature.

THOMAS JOSEPH SCHUETZ.
